TAPE DISPENSER

Joseph J. Ballato, Albany, and Laurence W. Brulin, New York, N.Y., assignors to Norton Company, Troy, N.Y., a corporation of Massachusetts

Filed Sept. 11, 1957, Ser. No. 47,709

Term of patent 14 years

(Cl. D74—1)

FIG.1

We claim:

The ornamental design for a tape dispenser, as shown and described.
